(Cl. D3—26)

FIG. 1

FIG. 2

FIG. 1 is a plan view of a baby bib embodying my new design.

FIG. 2 is a perspective view thereof as it appears in wearing position.

The essential features of my design reside in the solid line disclosure on the drawing.

The drawing is lined for color to establish that the top triangular kerchief portion is of a different color than the bottom rather than to show any specific color.

I claim:

The ornamental design for a baby bib, substantially as shown and described.
